(57) **CLAIM**

The ornamental design for a busbar for electrical connections, as shown and described.

DESCRIPTION

FIG. 1 is a top, front, right isometric view of an embodiment of an ornamental design for a busbar for electrical connections;

FIG. 2 is a front elevation view of the busbar of FIG. 1;
FIG. 3 is a rear elevation view of the busbar of FIG. 1;
FIG. 4 is a right side elevation view of the busbar of FIG. 1;
FIG. 5 is a left side elevation view of the busbar of FIG. 1;
FIG. 6 is a top plan view of the busbar of FIG. 1; and,
FIG. 7 is a bottom plan view of the busbar of FIG. 1.

The ornamental design that is claimed is shown in solid lines in the drawings. The broken lines in the drawings are for illustrative purposes only and form no part of the claimed design. Any dash-dot broken lines in the drawings are included to illustrate unclaimed surfaces or environment of the claimed design. Any dash-dot-dot broken lines in the drawings are included to define unclaimed boundaries of the claimed design.
